UNITED STATES PATENT OFFICE.

THOMAS EMIL GJORUP, OF MANSFIELD, OHIO.

COMBINATION RUBBER SIGNBOARD OR PANEL WITH DETACHABLE LETTERS AND FIGURES.

Application filed January 22, 1923. Serial No. 614,208.

To all whom it may concern:

Be it known that I, THOMAS EMIL GJORUP, a citizen of the United States of America, residing at Mansfield, in the county of Rich-
5 land and State of Ohio, have invented cer-
tain new and useful Improvements in Com-
bination Rubber Signboards or Panels with
Detachable Letters and Figures, of which
the following is a specification.

10 My invention relates to sign boards and
the like devices in combination with detach-
able letters and figures, and to the use of
rubber as material for such, and has for
one of its objects to furnish a sign board
15 or panel with a rubber surface and articles
representing letters and figures adapted to
be attached thereon without the use of any
binding substance whatsoever.

Another object of the invention is to fur-
20 nish a sign board or panel of such a na-
ture that articles representing letters, fig-
ures, etc. may be attached thereon and de-
tached therefrom without leaving any marks
25 or impressions or otherwise disfigure or in-
jure the rubber surface of the board or
the letters or figures themselves.

A further object of the invention is to
furnish a sign board or panel that may con-
30 sist of glass, covered with transparent rub-
ber sheeting, thus providing a device of
this kind that may be illuminated in dark-
ness by placing a light behind it. A fur-
35 ther object of the invention is to provide
means of constructing a sign-board and the
like for advertisement purposes or the like
of a substance that can be washed and
cleaned of dust, dirt, or other debris, so
40 that its cohesive quality will not be affected.

Furthermore, the object of this invention
45 is to furnish devices and articles of this
nature adapted to be used in places of busi-
ness, public institutions, etc., for advertising
and announcement purposes—and, in minia-
ture sizes, to provide an educational, in-
50 teresting, sanitary and unbreakable toy for
children.

With these and other objects in view, the
characteristic features and scope of the in-
vention will be readily understood from the
55 following description taken in connection
with the drawing forming a part thereof
wherein:

Fig. 1 is a perspective view of the sign
board or panel with a pigeon-holed cabinet
60 attached to the back thereof.

Figs. 2 and 3 illustrate the letters and fig-
ures and their construction.

Figure 4 is a detail cross-sectional view.

The board and panel, as represented by
A in Fig. 1, is generally to be constructed
65 of wood, pasteboard or similar material and
the front surface (or both surfaces) is cov-
ered with crude rubber sheeting or with a
rubber compound or rubberized fabric, that
have retained the cohesive property natural
70 to crude rubber, and may be of any suit-
able color. However, the board or panel
may also consist of plate glass covered with
a transparent rubber sheeting; when this is
the case, a light may be placed behind the
75 board or panel at night, thus providing an
illuminated sign. The board or panel may
have attached to the back part thereof a
case or pigeon-holed cabinet as represented
80 by C in Fig. 1, and wherein the letters
and figures may be stored when not in use.
The cabinet may be opened from the back
part thereof, or, as shewn in Fig. 1 the
board may be provided with hinges or hooks
85 to permit it to be opened.

The board or panel may also be suitably
framed as shown in the drawing represented
by B.

The letters and figures as represented by
D in Fig. 1, and as illustrated in Figs. 2
90 and 3, have a base of crude rubber, or
a rubber compound or rubberized fabric
that have retained the co-adhesive quality
of raw rubber, and are mounted with vul-
canized rubber, metal, porcelain or any other
95 suitable material, cemented or otherwise fas-
tened to the said base. E indicates a body
or base portion composed of crude rubber.
Reference numeral F indicates the face of
a letter which may consist of vulcanized
100 rubber, metal, or other material which is
secured to the outer portion of the case
through the medium of any well-known ad-
hesive material. Or the letters and figures
may be made entirely out of crude rubber,
105 rubber compound or rubberized fabric.

The letters and figures are placed on to
the rubber surface of the board or panel
by a slight pressure and retained in posi-
tion by means of the cohesive nature of the
rubber. They are detached from the board
110 by a slight pull. Attention is called to the
fact that the invention herein described
consists of providing a cover for a base
which is inherently cohesive or adhesive and

in providing objects such as letters, figures, emblems, or the like and making them of the same or similar material which is inherently cohesive or adhesive, whereby without the agency of any additional adhesive material a sign, advertisement or the like, can be made on the base cover and changed to suit the particular business or line of advertisement desired at a particular time. In other words so that the emblems, letters, or figures or other objects, can be changed periodically and without difficulty and without in any way marring, changing, manipulating, or affecting the base or cover in changing, removing, attaching or detaching the objects from the baseboard. It also provides means if desired, of facing the objects with different kinds of material such as porcelain, metal, glass or the like, by the use of additional adhesive material.

It further provides means of placing and arranging objects of different colors and different combination of colors, in different positions and means of reflecting different colors through a base of transparent material.

Having now particularly described and ascertained the nature of my said invention and in what manner the same is to be performed, I declare that what I claim is:

1. The combination of a base of suitable material, having a sheet of crude rubber attached thereto, which has retained its cohesiveness, objects having a base of crude rubber which are adapted to be mounted upon said crude rubber base and held thereto at any position by the mutual cohesiveness of the crude rubber cover of the base

and the crude rubber objects, and similar objects of different material representing different characters being adapted to be attached to the crude rubber objects through the medium of additional adhesive material, as and for the purpose described.

2. The combination of a base composed of transparent material, one surface of said transparent material being covered with a cohesive rubber compound, objects representing pre-determined characters made of crude rubber material mounted on said base and being adapted to be affixed thereto by mutual cohesiveness without the use of any adhesive material except the binding effect incident to crude rubber, said objects being also adapted to be detached therefrom each other without showing the effect of said attachment, as described and set forth.

3. The combination of a receptacle having a series of compartments for the reception of different kinds of emblems, a member made of crude rubber attached thereto which has retained its adhesiveness, and objects made of crude rubber which have retained their cohesiveness mounted and supported on said crude rubber member at predetermined locations by the mutual cohesiveness only of the crude rubber member and said objects, and separate similar objects of different material adapted to be attached to the first named objects by the interposition of adhesive material, as described and set forth.

In testimony whereof, I affix my signature.

THOMAS EMIL GJORUP.
